UNITED STATES PATENT OFFICE

JAMES S. ABERCROMBIE, OF HOUSTON, TEXAS, ASSIGNOR TO STEPHENS PUMP COMPANY,
OF BOUND ROCK, TEXAS, A CORPORATION OF DELAWARE

PUMP

Application filed January 15, 1932. Serial No. 586,908.

This invention relates to pumps.

It has for its object the provision of a new and improved pumping combination including a pair of power means and a pump, the construction and arrangement being such that the power means may be used successively and simultaneously to operate the pump.

Other objects will hereinafter appear.

10 The drawing illustrates a sectional elevation of the preferred embodiment of the invention; the pump being shown in detail; the power means, fragmentarily.

15 The pump shown is designed for pumping abrasive and corrosive fluids, and is particularly adapted for use as a mud or slush pump in deep well drilling operations. This general type of pump is shown by the patent to Charles D. Stephens No. 1,832,259, of November 17, 1931.

20 It comprises a pair of substantially frusto-conical barrels 1 and 2, which are spaced and axially aligned so that their base ends are adjacent each other. The barrels 1 and 2 define, respectively, the pumped fluid chambers 3 and 4. The barrel 1 has an intake valve 5, and an exhaust valve 6; the barrel 2, an intake valve 7 and an exhaust valve 8. The intake valves 5 and 7 permit entrance into the barrels of the pumped fluid from the common intake pipe 9; and prevent the escape of pumped fluid from the barrels into said intake pipe. The exhaust valves 6 and 8 permit the expulsion of pumped fluid from the barrels into the common exhaust pipe 10; and prevent the passage of fluid into the barrels from said exhaust pipe.

25 Mounted within and coextensive with the barrels 1 and 2 are the tubular, expandable members 11 and 12, preferably made of rubber. Each of these members 11 and 12 has an internal flange at one end and an external flange at the other connected and sealed to the end walls of its chamber by the means 30 shown.

The piston 13 is disposed between and extends into the openings in the adjacent ends of the spaced barrels 1 and 2 and the open inner ends of the tubular members 11 and 12. When the piston is in the position shown 50 by the drawing, the member 11 is expanded; the member 12, in its normal cylindrical shape. When the piston is moved to the right, the member 12 is expanded by the actuating fluid displaced therein by the piston, and the member 11 contracts when the piston is withdrawn therefrom. Upon expansion of member 12, the inlet valve 7 is closed; the outlet valve 8, opened, and the pumped fluid in chamber 4 is forced through 60 the exhaust pipe 10. Meanwhile, the contraction of member 11 has closed outlet valve 6, opened inlet valve 5, and drawn a fresh charge of pumped fluid through the inlet valve 5 into the chamber 3. 65

A reverse operation occurs when the piston is moved back into the position shown by the drawing. The tubular member 11 is expanded and the tubular member 12 contracted. Expansion of member 11 effects 70 closure of inlet valve 5, opening of outlet valve 6, and the expulsion of fluid from chamber 3 through exhaust pipe 10. Contraction of member 12 effects closure of outlet valve 8, opening of inlet valve 7, and suction of 75 fluid through inlet pipe 9 into chamber 4.

Now the present invention includes the connection to the piston 13 of rods 14 and 15, that extend in opposite directions from the piston through the barrels 1 and 2, respectively, to the exterior of the pump. To prevent the escape of fluid from the barrels about the piston rods, suitable packings indicated generally at 16 and 17 are provided. The outer end of the piston rod 14 is detachably 80 connected to a power means 18 by a coupling 19. The outer end of piston rod 15 is detachably connected to a power means 20 by a coupling 21.

The barrels 1 and 2, piston 13, and rods 90

14 and 15, are axially aligned. The numerals 18 and 20 indicate any suitable power means; for example, conventional steam engines.

When it is desired to repair power means 5 18, the coupling 19 may be removed to disconnect the rod 14 therefrom, and the power means 20 may then be used to operate the pump. If the power means 20 is in need of repair, the coupling 21 may be removed to dis- 10 connect the rod 15 therefrom, and the pump may then be operated by the power means 18. Or the piston rod 14 may be connected to the power means 18, and the piston rod 15 to the power means 20, and the power means used 15 simultaneously to supply greater power to the pump.

I claim:

1. The combination of a pair of power means; a pump between said power means 20 and having a piston, and a pair of piston rods connected to and extending in opposite directions from said piston toward said power means; and couplings to operatively and detachably connect each of said power means 25 to the rod adjacent thereto, so that said power means may be used successively and simultaneously to operate said pump.

2. The combination of a pair of power means; and a pump between said power means 30 and having a pair of barrels, each of said barrels having inlet and outlet means; a recipro- 35 ciprocable piston between and extending into each of said barrels; and a pair of piston rods connected to and extending in opposite directions from said piston through said barrels to the exterior of said pump; said barrels, piston and rods being in axial alignment, and each of said rods being detachably connected to one of said power means.

40 3. The combination of a pair of power means; a pump between said power means and having a barrel; said barrel having inlet and outlet means; a hollow expansible member in said barrel; a piston to expand and contract said member to draw fluid into said barrel through said inlet means and to expel it from said barrel through said outlet means; and a pair of piston rods connected to and extending in opposite directions from said 45 piston to the said power means; and couplings to separably and detachably connect each of said power means to the rods adjacent thereto so that said power means may be used successively and simultaneously to operate said 50 pump.

4. The combination of a pair of power means; and a pump between said power means and having a pair of barrels; each of said barrels having inlet and outlet means; a hol- 55 low expansible member in each of said barrels; a recipro- 60 ciprocable piston between said barrels and extending into each of said members to expand and contract said members to draw fluid into said barrels through said inlet means and to expel it from said barrels

through said outlet means; and a pair of piston rods connected to and extending in opposite directions from said piston through said barrels to the exterior of said pump; said barrels, piston, members and rods being in axial alignment and each of said rods being detachably connected to one of said power means.

In testimony whereof, I hereunto affix my signature.

JAMES S. ABERCROMBIE.
